SHAVING IMPLEMENT

John Bruecker, Chicago, Ill.

Application November 1, 1939, Serial No. 302,313

2 Claims. (Cl. 30—43)

This invention relates to shaving implements of the type known as dry shavers. It has more particular reference to the cutting action between the skin-engaging member or comb and the cutter blade which is rapidly moved across the inner side of the comb. It has further reference to that type of dry shaver employing an extremely thin, curved comb and a cutter blade which oscillates at a high speed and is responsive to centrifugal force for urging it against the inner side of the comb to cut off the hairs projecting through the openings in the comb.

The object of my invention is to improve the cutting action and to obtain closer and smoother shaving. To this end I have provided an improved cutter member having opposed acute angle cutting edges cooperating with the comb in such manner that each cutting edge strikes the projecting hair in a cutting action of high unit shearing force applied in a shearing plane directly along the underside of the comb. According to my invention the cutter is so shaped as to avoid or reduce initial bending of hair. This bending or distortion of the hair projecting through the comb would otherwise occur by reason of the body of the cutter striking and bending the individual hairs before the cutting edge engages them in the cutting action. My improved construction tends to avoid or reduce rhombic shape of the cut off pieces of hair and to produce sharp cutting and smoother shaving results.

Another object is to provide in a shaver of the character described a cutter having opposed cutting edges so shaped and positioned that a cutting action takes place in each direction of movement and the construction avoids entrapment of hair during the reverse stroke actions.

Referring to the drawing:

Fig. 1 is a cross section through the cutting head of a dry shaver of the kind shown in my application for patent, Serial No. 178,221;

Fig. 2 is a longitudinal section through the cutting head taken substantially on the section line 2—2 of Fig. 1, with some of the parts in elevation and omitting the drive element;

Fig. 3 is an enlarged fragmentary section through the comb and cutter; and

Fig. 4 is a similar section showing a modified form of cutter.

My improvements relate to the shape of the movable cutter member and its coaction with the stationary cutting member. These improvements are applied in a shaver of the type having an extremely thin, curved, skin-engaging

member which is perforated or otherwise formed to receive hairs to be cut and is commonly known in this art as the "comb," and a cutter blade which is moved at a high speed across the inner side of the comb and is so mounted as to be urged outwardly into cutting or shearing engagement with the inner surface of the comb by centrifugal force.

In the example here shown for purpose of illustration, the comb designated generally by 6 is of extremely thin metal flexed or formed to a curved shape. In this instance the comb is flexed and is retained in such form by means of a skeleton frame designated generally by 7 having semi-circular members 8, 9, 10, 11, 12 and 13 joined by longitudinal members 14 and 15. The comb is provided with suitable perforations 16 to allow for passage of the beard hair or other hair to the inner side and to provide cutting edges 17 at said inner side which function in the cutting of such hairs. The perforations may be of any suitable or preferred shape. A comb of this type associated with a skeleton frame so as to constitute a unit is claimed as subject matter of invention in my copending application above mentioned. As disclosed in my said application the comb unit is supported on end walls 18 and 19 of a head structure designated generally by 20, and suitable means such as retaining elements 21 engage the comb unit and hold it seated on the head structure.

In this example the cutter designated generally by 22 is carried by a holder 23 which in turn is provided with trunnion ends 24 journaled in the end walls of the head structure. Suitable means are provided for rapidly oscillating the cutter holder consisting in this instance of an eccentric pin 25 carried on a driving member 26 which rotates about an axis perpendicular to the axis about which the cutter holder oscillates and is driven by an electric motor or other suitable source of power, the eccentric pin 25 being engaged between opposed parallel members 27 fixedly carried by the cutter holder at the side of its axis opposite from the cutter proper. In this instance, the cutter 22 is in the form of a flat blade having a sliding fit in a slot 28 in a plane radial with respect to and intersecting the axis of the cutter holder. Also, a guide pin 29 on the blade is confined between opposed locating and guiding surfaces 30 so that the blade is retained against lengthwise displacement with respect to the inner surface of the comb. This is desirable in the particular structure here disclosed in order to maintain the cutting edges of

the cutter blade in proper cooperative relation with the cutting edges on the comb, insofar as location lengthwise of the comb is concerned. The blade is cut away at 31 to provide clearance for the members 9, 10, 11 and 12. It will be evident that when the member 26 is rotated at a high speed the cutter blade 22 will be oscillated in the arc "A," Fig. 1, and by reason of its support it is freely responsive to centrifugal force and will be urged by such force outwardly into shearing engagement with the inner surface of the comb. There is also provided a supplemental means such as a spring 32 acting between the cutter holder and the cutter to urge the latter outwardly so that in this particular instance the cutter is influenced in this movement by both the spring force and the centrifugal force. According to my invention, however, either or both of these forces may be utilized.

My invention contemplates improved cutting action between the skin-engaging member 6 and the cutter blade 22 characterized by the provision of acute angle cutting edges at opposite sides of the blade from end to end so that the undercut wall intersects the outermost wall at an acute angle. In the form shown in Fig. 3 the sides of the blade are hollow ground at 33 so as to provide walls 34 in acute angle relation to the end wall 35 and forming a sharp blade-like cutting edge 36 at the juncture of each wall 34 with the end wall 35. In the form shown in Fig. 4, the cutter blade is swaged, milled, or otherwise machined or formed at 37 to provide acute angle cutting edges. Here the angle is more acute than in Fig. 3; and this angle may be further reduced.

As a result of this construction the acute angle cutting edge 36 has improved cutting and shearing action. The effectiveness of the cutting edge 36 in its coaction with the cutting edge 17 at the inner surface of the comb depends on the angle of the cutting edges, the position of the hair with respect to the hole opening, and the distance of the hair from the effective cutting edge 17 at the time the moving cutter first engages the hair. With my improvement the stress concentration at the cutting edge is materially increased and this high unit shearing force, together with the tendency to avoid bending of the inwardly projecting hair makes for closer and smoother shaving. It reduces the tendency to bend the inwardly projecting hair prior to or during the cutting action, thus reducing and, to a degree, eliminating rhombic shape of the cut off pieces of hair. By severing the hair in this manner in a structure such as here disclosed, I am able to cut the hair close to the skin without irritation. Also, the acute angle cutting edge gives an easier cutting action and tends to avoid pulling of the hair. It will be observed that, by reason of location of the opposed cutting edges 36-36 in close proximity, one with respect to the other, the construction

avoids entrapment of hair during the reverse stroke actions.

In the form shown in Fig. 3, which is magnified approximately thirty diameters, the comb member is .002" in thickness; the openings 16 are .018" in diameter; the hole centers are spaced .045" apart; and the main body of the cutter is .022" in thickness and is reduced at the narrow portion by grinding to approximately .008". These dimensions are approximate as applied to this particular example. It should be understood, however, that the invention is not to be circumscribed by limitation to such dimensions. It will be evident from the foregoing that changes may be made in the size, shape and proportion of the parts within the scope of the appending claims, in which—

I claim:

1. In a shaving implement, an extremely thin, curved, skin-engaging member having hair receiving openings of such area as to permit ready passage of hair therethrough but to confine the skin from passing beyond its inner surface, a cutter blade substantially normal to the inner surface of said member undercut at opposite sides to provide sharp acute angle cutting edges, and means for rapidly oscillating the blade across the inner side of said member with the blade urged against said inner side, whereby a relatively high unit shearing force is obtained in the cutting action of each cutting edge on an interposed hair and the moving cutter severs the hair close to the skin without tending to initially bend that portion of the hair which projects within the comb member, the opposed cutting edges being in such close proximity, one with respect to the other, as to avoid entrapment of hair between the terminal end of the cutter blade and the skin-engaging member during the reverse stroke actions of the blade.

2. Shaving mechanism comprising a guard of thin sheet material adapted to have one of its surfaces pressed against the skin to be shaved, said guard being arcuately curved in at least one dimension and being formed with numerous small circular perforations for admitting hairs, and a cutter member for engaging the opposite surface of said guard, means for supporting and angularly moving said cutter member over said latter surface, said cutter member comprising a sheet metal strip having an edge of substantial thickness bearing against said latter surface and said strip extending in a plane substantially normal to the various portions of said latter surface as same come into contact therewith, the sides of said strip being both formed with a groove of substantially arcuate cross section along said edge, one side of each of said grooves terminating at said edge and forming a relatively sharp acute angle with the surface comprising said edge.

JOHN BRUECKER.
